ITEM RETAINING MECHANISM FOR
ACCOUNTING MACHINES

Walter A. Anderson, Bridgeport, Conn., assignor
to Underwood Corporation, New York, N. Y., a
corporation of Delaware

Application December 23, 1950; Serial No. 202,465

1. Claim. (Cl. 235—60.31)

This invention relates to adding and accounting machines and more particularly to an improved mechanism to retain indexed items in the indexing mechanism during total cycles.

One object of the present invention is to provide in a ten key accounting machine, a mechanism capable of retaining indexed items during total and sub-total cycles.

Another object is to provide an indexing mechanism normally ineffective to control the register actuators and which need not be reset prior to total and sub-total operations.

A further object of the invention is to provide in an accounting machine having automatic function controlling mechanism, means to temporarily disable the normal control of the indexing mechanism over the actuating means to permit taking of totals while an item is set in the indexing devices.

Still another object is the provision in an accounting machine of automatic mechanism to repeat print key set items interspersed with automatic total taking operations.

With these and other objects in view, the present invention consists in certain novel features of construction and combination of parts, the important elements of which are included in a description of a preferred embodiment of the invention hereinafter set forth with reference to the accompanying drawings in which.

Figure 1 is a right-hand side elevation showing the mechanism in its initial position.

Figure 2 is a partial right side elevation showing the machine at half cycle during sub-totaling or totalling operations.

Figure 3 is a top plan view showing the relative positions of the parts in normal position.

The present invention is described herein as embodied in an accounting machine similar in construction to the machine disclosed in Patent No. 2,194,270, issued to O. J. Sundstrand on March 19, 1940, to which patent reference may be had for details of construction not fully described herein.

Machines of this character include, generally, a numeral keyboard, type bars for printing the amount set up in the numeral keys, totalizers for computing and accumulating amounts set up in the numeral keys, function controlling keys and automatically operated controls for conditioning the machine for adding and subtracting operations, and enabling, sub-totaling and totalling of the amounts accumulated in the totalizers. The machine also includes a cylindrical platen carried in a traveling paper carriage arranged

for tabulation to various columnar positions and for return to its initial position.

Referring to Figure 1 of the drawings, a representative one of the ten numeral keys is illustrated at 10. The key 10 is mounted for vertical slideable movement in a frame 11 affixed in the machine base, and normally engages a cradle 12 by a lug 13 on the key, said cradle 12 being pivotally supported in bushings 14 in the frame 11. A link 15, see also Figure 3, connects the cradle 12 and a rocker arm 16. Pivotedly connected to a stud 17 on the rocker arm 16 is a push rod 18 slidably supported in a post 19 firmly secured in a swinging arm 20. The swinging arm 20 is pivotally supported in the frame 11 and is provided with a pin 22 engaging in a slot 23, Figure 3, of a block 24. Block 24 is slidably supported on a shaft 25 and is acted upon by an escape mechanism (not shown) which, upon the depression of one of the keys 10, indexes the block 24 rightwardly on the shaft 25 denomination by denomination. During the indexing movement of the block 24, the swinging arm 20, by means of the slot 23 and the pin 22, rotates clockwise, to place the plungers 18 in alignment with one line of a field of stops 26 slidably supported in a frame 27 fixed in the machine.

Upon the depressions of a key 10 the plunger 18 is moved rearwardly, by means of the cradle 12, the link 15 and the rocker arm 16, to strike the stop 26 with which it is aligned and move the stop 26 into an effective position with respect to a line of tail pins 28. The tail pins 28 are supported for vertical sliding movement in a block 29, and are slidably connected to swinging arms 30 pivoted on the lower ends of type bars 31. Type bars 31 are mounted for vertical slideable movement on a bar 32, Figure 1, affixed in the machine frame and carry type 33 for printing amounts on work pieces supported by a platen 34.

The stops 26 are reset to their initial position by a cam post 99 on block 24 during the return of swinging arm 20 and block 24 to their initial position which normally occurs near the end of each machine cycle. During certain operations of the machine, it is desirable to retain the amount set up by the numeral keys 10 during a plurality of successive machine cycles. Such repeat entering of the indexed amount is old in the art and fully described in Figures 10 to 12 of the above Sundstrand Patent No. 2,194,270, and will be but briefly described herein. Referring to Figure 3, a link 100 is connected between swinging arm 20 and one arm of a bell crank 101 pivoted on the machine base. A link

102 pivoted on the other arm of bell crank 101 extends rearwardly and is biased into the path of a power operated arm 103 by a spring 104. Near the end of each machine cycle, arm 103 normally strikes link 102 to rock bell crank 101 and through link 100 restore arm 20 to its normal position shown in Figure 3.

To prevent such restoration of arm 20, the rear end of link 102 may be moved out of the path of arm 103 by rocking a bell crank 105 pivoted on a stud 106. Bell crank 105 has a stud 107 normally free of link 102 but which stud will, upon counterclockwise rotation of bell crank 105, engage the left side of link 102 and move it out of the path of arm 103. Bell crank 105 may be moved to the disabling position by a manually operable repeat key 108 or by a carriage operated slide 109 having a depending stud 110 contacting an arm of bell crank 105. Key 108 when depressed cams a slide 111 to the left to rock a lever 112 clockwise to engage an ear 113 on the forward arm of bell crank 105 and thereby rock link 102 to the ineffective position.

In some forms of accounting work, it is desirable to print a crossfooter sub-total on a form between the first printing of an item and a repeat printing of that item. In prior machines of this type, this could not be done for during the total taking operation, the usual crossfooter 116, Figure 1, is engaged with racks 117 connected to type bars 31, to limit in conjunction with the customary transfer mechanism 118, the rise of type bars 31. In such machines, the block 29 for tail pins 28 must be in the normal position to prevent a set pin 26 from interfering with the movement of type bars 31, and restoration of block 29 to such a position effected a resetting of pins 26 by the reset post 99 on block 24.

The present invention provides means whereby a total or sub-total of the amounts entered into the crossfooter 116 may be taken and printed while the debit or credit amount set up in the stops 26 by the keys 10 is retained for repeat printing at a later time. To this end the tail pin block 29 is firmly secured to a formed member 35 slidable on screws 36 in the block 24. Block 24 and member 35 supported thereon are slidable on shaft 25, and member 35 has secured to its lower edge a pair of rollers 37, engaged in a transverse channel 38 forming part of a member 39 slidably supported on screws 40 in a shelf 41 affixed to the frame 27 and on a shaft 42 rigidly supported in the frame. Depending lugs 43 on member 39 are pivotally connected to links 45 which are connected at their forward ends with depending legs of a bracket 49. The bracket 49 is secured to a cradle 50, pivotally supported on the shaft 42 and having an upstanding arm at its right end. A link 53 is pivoted to the upstanding arm of cradle 50 and is provided at its other end with a slot 54 in which is positioned a pin 55, affixed in a lever 56 pivoted in the machine frame. A spring 58 connected between pin 55 and a stud 57 in link 53 normally holds link 53 with the forward end of its slot 54 in engagement with pin 55. Lever 56 is tensioned by a spring 63 to a counterclockwise position wherein normally, that is, with the machine in its initial position, a roller 59 secured to lever 56 rests in a step 60 provided in a cam member 61 rigidly secured on the machine main rock shaft 62. With lever 56 in this position, the cradle 50 is positioned in its counterclockwise position, Figure 1, the links 45 holding block 29 in its rearward position with the pins 28 out of vertical alignment with any of the stops

26 which may have been extended by the depression of the keys 10.

The main rock shaft 62 rocks counterclockwise as seen in the drawings through an arc of approximately 90° for the forward stroke and returns through the same arc during the return stroke of the machine cycle.

During an item entering operation of the machine and immediately upon the start of the forward stroke of the shaft 62, the cam 61 forces the roller 59 rearwardly to move the lever 56 clockwise against the urge of spring 63. Since the lever 56 is yieldably connected by spring 58 with the link 53, link 53 is drawn rearwardly thereby to rock the cradle 50 to its rearward position, as shown in dot and dash line in Figure 1, whereupon, by means of the links 45, the member 39 is drawn forwardly. As the rollers 37 are in engagement with the channel 38 in the member 39 at all times, the member 35 is also drawn forwardly to position the block 29, and the tail pins 28 supported thereby under such stops 26 as may have been extended by the keys 10. During the remainder of the cycle, the type bars 31 and tail pins 28 rise against the set stops 26 to position the proper type 33 for printing the indexed amount. At the end of the return stroke of shaft 62, roller 59 drops into step 60 of cam 61 to permit spring 63 to return block 29 and tail pins 28 to their initial position.

In prior machines of the type described, a total or sub-total printing operation must be preceded by a spacing stroke or blank cycle to reset the transfer mechanism 118 for crossfooter 116 and to engage the crossfooter 116 with the racks 117 corresponding to the sign of the total contained in the crossfooter.

Normally, in such prior machines the spacing stroke or blank cycle is taken when all of the stops 26 are reset to their initial position and the block 24 is fully returned to its extreme leftward position, as shown in Figure 3. In this position, the tail pins 28 of the prior machines are under a "0" stop plate 67 which prevents any type bar 31 from moving more than one step from the restored position to the "0" printing position. During the movement of type bars 31 to "0" printing position, any rack bar 117 which had been released by a transfer stop pawl 118 is lifted sufficiently to enable the transfer stop pawl 118 to be restored by its conventional restoring means, to the rack restraining position shown during the first half machine cycle. All racks 117 are thus latched at the "0" position during such blank cycle. During the second half of the machine cycle, the crossfooter 116 is reengaged by a mechanism described in the above patent with the add or subtract racks 117 to enable a total of the correct sign to be taken in the next cycle.

In the present embodiment, however, the blank stroke and the total cycle are, when the machine is set to repeat an item, to be taken without a change in the indexed position of block 24 and without resetting of stops 26. Tail pins 28 are not then all under "0" stop plate 67 and means must be provided to prevent type bars 31 from rising above the "0" position during the blank cycle. To prevent such rise of type bars 31, a sector lock is provided which is identical in construction and mode of operation with that disclosed in Patent No. 2,308,144, issued to W. A. Anderson on January 12, 1943. The sector lock includes, generally, a member 70, Figure 1, pivotally supported on a shaft 71 in the machine frame. A roller 72, secured thereto, is tensioned

by a spring 73 to bear against a cam member 74 pivotally supported in the machine frame and acted upon by an automatic control, not shown herein, actuated from the traveling paper carriage. A depending leg 75, forming part of the member 70 is normally held by spring 73 in a position clear of the rear ends 76 of the type bars 31, as is illustrated in Figure 1. During carriage controlled blank cycle operations, the carriage depresses the automatic control operating the cam member 74, causing member 74 to cam roller 72 and member 70 clockwise to position depending leg 75 over the rear end 76 of the type bars 31 and prevent their rising above the "0" position during this cycle.

Since, as previously described, the tail pins 28 are normally moved by the cam 61 to underlie the stops 26, the present invention provides means to prevent such movement during the taking of a sub-total, or total, from the cross-footer 116 to leave the type bars free to rise under the control of the adding wheels above. For this purpose the crossfooter total control slide 77, the crossfooter sub-total control slide 88 and control slide 78 which is provided to enable the taking of a total from the rear registers (not shown) are each provided with a depending lug 79, Figures 1, 2 and 3. Pivotally supported on a rod 80 fixed in a bracket 81 on the machine base is a cradle 82 having a forward upstanding portion extending into the path of movement of the lugs 79. Forming part of the member 82 is a leaf 84 extending rearwardly to normally rest on a lug 85, forming part of the bracket 81. A spring 86 connected between the bracket 81 and cradle 82 normally holds the leaf 84 of cradle 82 just clear of an extended portion of the right leg of bracket 49, to normally enable movement of the tail pins 28 to printing position during item entering operations as above described.

When a crossfooter total or sub-total or a register total is to be printed, the corresponding slide 77, 88 or 78 is moved forwardly either by the manual operation of control keys 89, 90 and 91 through their cradles 92 or automatically from the carriage as in Patent No. 2,194,270 above. Upon the forward movement of any of the total control slides 77, 78 or 88, the lug 79 thereon strikes the upstanding forward portion of member 82, to rock the member counterclockwise and place the leaf 84 forming part thereof in front of the lower right arm of bracket 49, to prevent rocking of cradle 50 by the lever 56, during the following machine cycle as shown in Figure 2. During cycling of the machine and the consequent rocking of the lever 56 by the cam 61 the pin 55 rides freely in the slot 54 of link 53, stretching the spring 58, while the leaf 84, under the urge of the stretched spring 58,

5 60

holds the cradle 50, slide 39 and tail pins 28 firmly in their normal rearward position where they are free of the set stops 26 during the rise of the type bars 31 to position to print the total amount.

After printing of such a total the carriage may be tabulated to another columnar position wherein the amount retained in the stops 26 may be repeat printed and the stops 26 reset during the return stroke of the machine cycle.

The above description is of a preferred embodiment only of the invention and is not to be taken in a limiting sense as the invention is susceptible of use in many different machines without departing from the principle thereof. The scope of the invention is to be limited only by the following claim.

What is claimed is:

In an accounting machine of the class described having a register, printing members, a plurality of indexable stops arranged denominational in rows, feeler members connected to said printing members and shiftable across said field of stops into alignment with successive denominational rows thereof, a guide slidably supporting said feeler members and shiftable therewith, a block member slidable in a direction across said rows of indexable stops, a shifting member mounted on said block to shift said guide and said feelers, said member being shiftable on said block in a direction perpendicular to the plane of said stops, a channel member also shiftable in said perpendicular direction, means on said shifting member engaged in said channel member, members including a resilient connection operated by said cycling means to shift said channel member and thereby said feeler members toward said field of stops prior to advance of said printing members whereby the indexed ones of said stops will differentially limit movement of said printing members, a total control member operable to enable said register to limit movement of said printing members, and means operable by said total control member to lock said channel member against movement by said cyclically operating members, enabling said register alone to limit movement of said printing members.

WALTER A. ANDERSON.
